UNITED STATES PATENT OFFICE.

JOSEPH OBERLE, OF CHICAGO, ILLINOIS.

WASTE-BURNER.

1,116,473.

Specification of Letters Patent.

Patented Nov. 10, 1914.

Application filed May 29, 1914. Serial No. 839,721.

To all whom it may concern:

Be it known that I, JOSEPH OBERLE, a subject of the Emperor of Austria-Hungary, residing at Chicago, county of Cook, and State 5 of Illinois, have invented certain new and useful Improvements in Waste-Burners, of which the following is a specification.

The invention has for its object the provision of a waste burner intended particularly 10 for consuming waste paper and other similar refuse and is intended to be moved about from point to point but at the same time so constructed that it will be self-supporting when standing in a given position, and moreover adapted to be easily moved or overturned so as to dump out any unconsumed refuse or the like. When inventions of this 15 character are actually in use, the basket or body of the burner sometimes becomes heated 20 so as to make it difficult to overturn or empty same manually and very frequently the refuse or waste paper is consumed in a bonfire which it would be dangerous or undesirable for the operator to approach. This invention, accordingly, provides a basket which 25 cannot only be overturned or emptied without the necessity of touching the basket itself, but which can moreover be operated at a 30 particular spot at which the contents are to be dumped. In this way the operator can stand several feet from the fire or the point of dumping and yet empty the basket of its 35 contents without difficulty.

In the drawings, Figure 1 is an elevation 40 of the invention showing the basket in the position assumed when the waste paper or the like is being collected; Fig. 2 is a view showing the parts in the positions respectively assumed by them when the contents 45 are being or have been emptied; and Fig. 3 is an end elevation looking toward the right in Fig. 1.

The basket 1, which may be made of any 50 suitable wire mesh construction and which may, if desired, be provided with the lid or cover 2, is of any desired size or shape, but may conveniently be in the form of a truncated cone as customary with waste baskets and the like. The basket is preferably made 55 of some reticulated material, such as woven wire, in order to permit access of the air during the combustion process. At one side the straps 3 are fastened to the basket which

said straps are bent at their lower ends 4 55 away from the body of the basket and formed at the extreme ends into loops 5.

The wheels 6 are mounted upon trunnions 7, and extending from one of these trunnions 7 to the other is the standard 8 comprising 60 preferably two vertical arms and a horizontal arm or arms 9. In the drawings, the horizontal arms are shown as having a bent portion 10 but this feature may be omitted if desired.

Extending from the trunnions 7 is a base 11, which is preferably V-shaped, and to said base the hollow handle 12 is secured. A strut 13 is fastened at some suitable point to the base and a chain 14 provided with a 70 ring or handle 15 at one end and secured to the basket 1 at its other end is slidably received within the hollow tube or handle 12. Said chain is secured to the basket 1 upon the same side of the basket as that to which the straps 3 are fastened. After the basket 75 has been filled with paper or the like and when it is desired to empty the same, the operator gives a sharp pull upon the chain, pulling the same toward the right, Figs. 1 80 and 2. This causes the basket to be moved from the full-line position of Fig. 1 toward the dotted line position. By giving the chain a sharp pull the operator can almost invariably impart sufficient momentum to 85 the basket to cause same to rock upon the pivots and carry the center of gravity of the basket to the left of the pivot 9 to which it is obvious the hinge-like or loop-like ends 5 of the straps 3 are secured. As the basket 90 passes to or toward the position depicted in Fig. 2, the chain will be drawn from right to left and will move until the ring 15 engages the right end of the hollow tube or handle 12, thus preventing further movement of the basket and holding it in the 95 position depicted in Fig. 2. If the chain 15 be again pulled toward the right, the basket will return to starting position, that is to the position of Fig. 1, and when the basket 100 is in the position of Fig. 1, the ring 15 will assume the position shown in full lines in Fig. 1. Obviously when the basket is emptied the ring 15 will be pulled from the full-line position to the dotted line position of 105 Fig. 1, which movement will suffice to set the basket in motion and impart sufficient momentum thereto to make certain that the

100

105

basket will be dumped. As the basket passes over the member 9, the chain will be drawn from the dotted line position of Fig. 1 to the position of Fig. 2.

5 It should be understood that many changes in the details of construction can be made without affecting the scope of the invention and that numerous appliances well known in the art may be provided by which 10 the operator can control the basket while holding the handle 12 at or near its right end.

I claim as my invention:

- 15 1. In a device of the character described, the combination of a pair of wheels, a horizontally-disposed member supported thereupon, a basket having arms outwardly projecting from said basket and in pivotal relation to said horizontal member, a chain secured to the basket upon the side adjacent said horizontal member, and a handle having means for supporting said chain and through which said chain is adapted to slide.
- 25 2. In a device of the character described, the combination of a pair of wheels, a horizontally-disposed member supported thereupon, a basket having arms outwardly projecting from said basket and in pivotal relation to said horizontal member, a chain secured to the basket upon the side adjacent said horizontal member, and a handle formed of a tubular member, said chain being slidably received within said tubular member, said chain being provided with
- 30
- 35

means to limit its movement with respect to said tubular member.

3. In a device of the character described, the combination of a basket, a pair of wheels, a platform-like member secured to said wheels and upon which the bottom of said basket is adapted to rest, a standard projecting upwardly from said platform-like member, members secured to said basket and in hinge-like relation to said standard, a chain secured to the basket at a point upon that side of the basket normally nearest the wheels, and a handle secured to said platform-like member, said handle being adapted to guide the movement of said chain.

4. In a device of the character described, the combination of a pair of wheels, a basket having arms which project from said basket adjacent the upper edge of said basket, said arms being upon that side of the center of gravity of the basket normally nearest to the wheels, a standard supported by said wheels and with which said arms are in pivotal relation, a chain secured to the basket upon the same side thereof as said arms, and a handle in connection with said wheels and with which said chain is in slid-able relation.

In testimony whereof I hereunto affix my signature in the presence of two witnesses.

JOSEPH OBERLE.
